US0D1059105S

(12) **United States Design Patent** (10) **Patent No.:** **US D1,059,105 S**
(45) **Date of Patent:** **** Jan. 28, 2025**

(54) **HEADREST ASSEMBLY**

(71) Applicant: **SHEN ZHEN STAND BY ME TECHNOLOGY LIMITED**,
Guangdong (CN)

(72) Inventor: **Zhiping Zhou**, Guangdong (CN)

(73) Assignee: **SHEN ZHEN STAND BY ME TECHNOLOGY LIMITED**,
Guangdong (CN)

(**) Term: **15 Years**

(21) Appl. No.: **29/860,347**

(22) Filed: **Nov. 18, 2022**

(30) **Foreign Application Priority Data**

Sep. 30, 2022 (CN) 202230655414.3
Sep. 30, 2022 (CN) 202230655415.8
Sep. 30, 2022 (CN) 202230655426.6

(51) **LOC (15) Cl.** **06-06**

(52) **U.S. Cl.**

USPC **D6/716.5**; D12/416

(58) **Field of Classification Search**

USPC D6/356, 595, 596, 601, 606, 716, 716.5;
D12/400, 415, 416; D24/191
CPC A47C 7/38; A47C 7/383; B60N 2/882;
A47G 9/1081; A61H 2205/04

See application file for complete search history.

(57) **CLAIM**

The ornamental design for a headrest assembly as shown and described.

DESCRIPTION

FIG. 1 is a front, right and top perspective view of a headrest assembly, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right and top perspective view of the headrest assembly shown in an environment of use.

The broken lines depict environmental structure and form no part of the claimed design.

1 Claim, 9 Drawing Sheets
